UNITED STATES PATENT OFFICE

OTTO H. LIEBICH, OF CHICAGO, ILLINOIS, ASSIGNEE TO THE KOHLER-LIEBICH CO., OF CHICAGO, ILLINOIS, A CORPORATION OF DELAWARE

PERCUSSION-TYPE INSTRUMENT

Application filed September 10, 1928. Serial No. 205,838.

In percussion musical instruments for use in combination with organ installations and the like, difficulty has been encountered due to the fact that the resonators or tone intensifiers particularly for the low notes were particularly long and projected out of the bottom of the sound box of the instrument thereby requiring an extremely large amount of space to properly mount the percussion instrument in an organ or any other place where space is at a premium. Trouble has also been encountered in percussion instruments due to the mode of mounting or securing the resonators in the sound box without 10 adequate facilities for preventing leakage of air.

This invention relates to an improved type of percussion musical instrument adapted for use in organ installations and the like, and 20 constructed with the resonators for the low notes divided into sections projecting in opposite directions from the sound box and parallel to the sounding bars to reduce air friction to cause intensification of the tones.

25 It is an object of this invention to provide a percussion type musical instrument wherein the use of long resonators is eliminated by the use of sectional resonators projecting in opposite directions from the sound box to 30 permit the instrument to be conveniently mounted in a shallow compartment with both the resonators and the sound bars disposed in a perpendicular position.

It is also an object of this invention to 35 provide a percussion type musical instrument having resonators inserted into grooved openings in the sound box through felt bushings and through washer plates of insulating material whereby an airtight or non-leaking 40 joint is provided between the resonators and the sound box to securely hold the resonators in a suitable position.

It is an important object of this invention to provide an improved percussion type musical instrument wherein the sound box is arranged to receive the resonators constructed in sections with said sections projecting in opposite directions from the sound box and parallel to a sound bar with the inner ends 45 of said resonator sections projecting through

felt bushings and through sound insulating washer plates which are adjustably mounted on the exterior of the sound box by means of screws or the like to permit compression of the felt bushing to insure an airtight fit 55 around the seamless resonators to securely hold the same in a suitable position.

Other and further important objects of this invention will be apparent from the disclosures in the specification and the accompanying drawings.

This invention (in a preferred form) is illustrated in the drawings and hereinafter more fully described.

On the drawings: 65
Figure 1 is a front elevation of an organ casing or the like, having a plurality of percussion musical instruments of different types embodying the principles of this invention mounted therein with the resonators 70 and sound bars disposed vertically.

Figure 2 is an enlarged longitudinal section taken through the middle percussion instrument on line II—II of Figure 1.

Figure 3 is an enlarged longitudinal section of the upper instrument taken on line III—III of Figure 1. 75

Figure 4 is a vertical side view taken on line IV—IV of Figure 1, showing the ends of the various instruments mounted within 80 the casing.

Figure 5 is an enlarged fragmentary detail section taken on line V—V of Figure 1, illustrating the method of mounting the resonator sections in the sound box. 85

Figure 6 is an enlarged fragmentary detail section taken on line VI—VI of Figure 1, illustrating the method of mounting one of the shorter resonators in a sound box.

Figure 7 is a fragmentary sectional view taken on line VII—VII of Figure 5.

Figure 8 is a longitudinal section of the upper instrument taken on line VIII—VIII of Figure 3 with the resonators shown in elevation. 90

As shown on the drawings:
The reference numeral 1 indicates a shallow case or box which may form a portion of an organ and which serves as a support within which a plurality of improved per-

ussion type musical instruments may be supported in parallel horizontal relation, thereby requiring a comparatively small amount of floor space. As illustrated in Figure 1, three different types of percussion instruments are illustrated.

The middle or intermediate percussion instrument will now be described in detail. This instrument comprises a sound box or 10 sound reflecting member constructed of wood or other suitable material, said box comprising a back wall 2 and a front wall 3 which is supported opposite the back wall 2 by means of a top wall 4 and a bottom wall 5. 15 The ends of the sound box are closed by end walls 6. The sound box is divided into a plurality of chambers 7 (Figure 2) formed by a plurality of partitions 8 disposed parallel to one another transversely of the sound box. 20 The front wall 3 of the sound box is provided with a row of apertures or openings 9, one for each of the tone chambers 7.

Secured at spaced intervals on the front wall 3 of the sound box are a plurality of 25 screw eyes 10 and 11, respectively. Threaded through the upper screw eyes 10 is a single heavy silken cord 12, and threaded through the lower screw eyes 11 are two silken cords 13. The ends of the cords 12 and 13 are 30 secured to the end screw eyes. The silken cords 12 and 13 are provided for the purpose of supporting a plurality of metal or wooden tone bars 14 which are graduated in length in the arrangement illustrated in Figure 1 to 35 produce the required notes of a musical scale when the sound bars are struck to vibrate the same.

Each of the tone bars 14 has inserted 40 through an aperture near the upper end thereof of a retaining screw 15 each of which projects through a rubber insulating sleeve 16 and through a suitable felt washer 17 engaged on the outer end of each screw between the tone bar and the head of the screw (Figure 45 6). The apertured ends of the tone bars 14 rest on the cord 12, while the lower or opposite ends of the tone bars are disposed between the double cords 13. Each of the tone bars or sound members 14 is mounted to permit 50 free vibration thereof in response to a blow imparted thereto to give forth the desired tone. The tone bars are mounted so that each bar is disposed in front of a sound box opening 9 each communicating with the 55 sound chamber 7 for that particular tone bar. The tone bars 14 are arranged with adjacent tone bars four semitones apart, thereby affording an arrangement which eliminates the disagreeable tone interference 60 perceptible in percussion instruments wherein the bars are not mounted by this method. By suspending the tone bars on the single contact points properly insulated at their nodal line insures unhindered and perfect 65 vibrations of the bars.

The top and bottom walls 4 and 5 of the sound box are each provided with a plurality of openings 18 provided with grooves 19 and 20 affording a stop flange 21 as clearly illustrated in Figures 5 and 6. Seated in each of the grooves 20 is a flexible or resilient bushing 22 constructed of felt or other suitable material. Mounted on the respective top and bottom walls 4 and 5 of the sound box over each of the openings 18 thereof, is a washer 23 constructed of sound insulating material such as fiber or hard rubber. Each of the washers 23 is provided with an opening of a diameter corresponding with the inner groove 19 of the opening 18 and substantially equal with the inner diameter of the felt bushing 22. Each of the washers is mounted in position by means of a plurality of screws 24 which may be adjustably secured into position to hold the respective washer clamped against the felt bushing to compress the same in position. Each of the felt bushings may thus be gradually compressed from time to time by simply tightening the screws 24 until the washers come directly into contact with the walls of the sound box upon which they are mounted.

Engaged through each of the washers 23 and projecting through the felt bushing and snugly into the groove 19, is the inner end of 95 a resonator or tone intensifying tube 25 preferably constructed of seamless tubing of brass, fiber, nickel or wood. The resonator tubes which are closed at the outer ends may be cylindrical, square, octagonal or of any 100 preferred shape desired.

The particular mode of insertion of the resonators 25 affords a tight fit for the resonators obviating the leakage of air from the sound box between the resonators and the sound box openings in which they are 105 engaged.

The middle percussion instrument is arranged with the resonators parallel to the tone bars 14, thereby affording an instrument which requires a small amount of space when installed in an organ or any place where the space is at a premium. In this form of percussion instruments the tone bars are arranged in two groups. The tone bars for the first group are mounted on the left half of the sound box looking at Figure 1, and comprise the tones C, E, G#, A#, D# and D. The second group of tone bars are mounted on the right half of the sound box 110 looking at Figure 1, and comprise the tones C#, F, A, B, G and D#. The tone bars for each group are arranged with the largest bars near the ends and with the other bars placed in graduated relation inwardly toward the center from both ends of the group. An important feature of the novel arrangement of the tone bars of each group lies in the fact that the tones of adjacent tone bars are four 115 semitones apart which allows increased vol- 120

ume of tone and the elimination of interference. The mode of suspension of the tone bars permits unhindered vibration of the tone bars when struck with a beater or a hammer.

Attention is called to the fact that the resonators for the tone bars C, E, F# and D, for the first group, and C#, F, G, and D# for the second group of tone bars, are constructed of two sections with the one section projecting upwardly from the top sound box wall 4 and the other section projecting downwardly from the bottom sound box wall 5. The two sections are in axial alignment with one another and are associated with and parallel to a particular tone bar as clearly illustrated in Figure 1. The use of the sectional resonators replaces the single long resonators heretofore used and, furthermore, reduces the friction of the air over that encountered in long resonators so that in the present method the use of the sectional resonators reduces the friction of the air traveling in the resonators and thereby greatly intensifies the tones produced. Associated with the tone bars G# and A# of the first group and A and B of the second group, are single or one piece resonators which project upwardly from the top sound box wall 4. There are no openings in the bottom sound box wall 5 associated with the tone bars G#, A#, and A and B. It will thus be noted that the lower tones of each group of tone bars have sectional resonators associated therewith, while the higher tones only have unitary resonators associated therewith which are graduated in length depending upon the tones.

By providing a percussion instrument with sectional resonators where needed parallel to their respective tone bars, an instrument is provided which may be mounted in a comparatively shallow recess or box which is highly desirable in organs and similar instruments where the floor space is extremely limited.

The upper and lower percussion type musical instruments illustrated in Figure 1 are constructed similar to the middle percussion instrument and the resonator tubes for the lower notes of said instruments are mounted in the tone box similar to the arrangement illustrated in Figures 5 and 6 of the drawings. The shorter or high pitched tone bars of the lower and upper instruments are mounted above openings in the sound box front board, and said openings have associated therewith short resonator cylinders of different lengths depending upon the respective lengths or size of the tone bars with which they are associated. The end tone bars of these instruments have sound compartments associated therewith with the compartments for the lower notes having resonator tubes projecting therefrom. The upper

and lower percussion instruments illustrated in Figure 1 and the detailed showing of the upper instrument as illustrated in Figures 3 and 8 are not described in detail since an adequate detailed description has already been given in connection with the middle instrument which covers all of the patentable features of the present invention. While embracing the improved mounting for the resonator tubes they do not embrace the use of sectional resonators. The showing of the three types of percussion instruments is used to illustrate the possible combination of percussion instruments of this type for use in organs and similar instruments.

I am aware that many changes may be made and numerous details of construction may be varied through a wide range without departing from the principles of this invention, and I, therefore, do not purpose limiting the patent granted hereon, otherwise than necessitated by the prior art.

I claim as my invention:

1. A percussion musical instrument comprising a sound box, grooved openings therein, flexible bushings seated in the grooves of said openings, washers secured to said sound box to hold said bushings in place, resonators projecting through said washers and through said bushings and seated in said openings, and tone bars supported on said sound box above the openings therein.

2. In a percussion musical instrument of the class described, the combination with a sound box, of sectional resonators supported therein with the sections of each resonator connected by an enlarged chamber in said sound box.

3. In a percussion musical instrument of the class described, the combination with a sound box, of sectional resonators supported therein with the sections of each resonator projecting in opposite directions from the sound box.

4. In a percussion musical instrument of the class described, the combination with a sound box, of tone bars supported thereon, and sectional resonators projecting from the sound box and parallel with said sound bars, with the sections of each resonator projecting in opposite directions from the sound box and axially aligned with one another.

5. In a musical percussion instrument of the class described, the combination with a sound box having a grooved opening therein to afford a stop flange, of a resonator tube projecting into said opening with one end of said tube seated on said stop flange, a bushing seated in said grooved opening and engaged around said resonator, a perforated washer through which said resonator projects, and means for adjustably securing said washer to the sounding box to compress said bushing to securely hold the resonator in position.

6. In a percussion musical instrument of the class described, the combination with a sound box having a grooved opening therein, of a bushing seated in said opening, a resonator projecting through said bushing and into said opening, and a washer secured to said sound box around said resonator to hold the bushing compressed. 70
7. In a musical percussion instrument of the class described, the combination with a sound box wall having a grooved opening therein to afford a stop flange, of a resonator tube projecting into said opening and seated against the stop flange, a bushing of flexible material engaged around said resonator and seated in a groove of said opening, and an insulating washer on said sound box to hold the bushing in place and afford a support for said resonator. 75
8. A percussion musical instrument comprising a sound box having tone bars arranged thereon to give a succession of major thirds with adjacent tone bars four semitones apart, and sectional resonators positioned parallel to the tone bars with the sections of each resonator projecting in opposite directions from said sound box. 80
9. A percussion musical instrument comprising a sound box having tone bars mounted thereon and arranged in the order shown and described to give a succession of major thirds with adjacent tone bars four semitones apart, and resonators mounted on said sound box parallel to the tone bars with the resonators for the low tones constructed in sections projecting from the sound box in opposite directions. 85
10. A percussion musical instrument comprising a sound box, tone bars mounted thereon arranged in groups with each group arranged so that adjacent tone bars are four semitones apart, and resonators projecting from the sound box and parallel with said tone bars, said resonators being of unitary and sectional construction with the unitary resonators associated with the high pitched tone bars and with the sectional resonators associated with the lower pitched tone bars with the sections of each resonator projecting in opposite directions from the sound box. 90
11. A percussion musical instrument comprising a sound box having openings therein, partitions in said sound box to divide the same into compartments, one associated with each of said openings, tone bars supported on said sound box above the openings, and sectional resonators projecting from the sound box and communicating with said compartments, said resonators having the sections thereof projecting in opposite directions from the sound box and parallel to the respective tone bars. 95
12. In a musical instrument of the class described, a sound box having a grooved opening therein, a felt bushing seated in said grooved opening, a resonator projecting through said felt bushing and into said opening, and a washer secured on said sound box for compressing the bushing to form an air-tight joint around said resonator. 100
13. In a percussion musical instrument, the combination with a sound box and the tone bars thereof, of sectional resonators supported on the sound box with the resonators constructed of short sections projecting in opposite directions to reduce the air friction to intensify the tones. 105
14. A percussion musical instrument comprising a sound box adapted to be mounted in a horizontal position upon a vertical support, screw eyes secured in the front face of the sound box, cords threaded through said screw eyes, tone bars supported upon said cords, screw members engaged through apertures in said tone bars and secured in the front wall of said sound box to retain the tone bars from displacement on said cords, and tubular resonators projecting upwardly and downwardly from the top and bottom walls of said sound box and parallel to said tone bars. 110
